LABELING MACHINE

George W. von Hofe, Bound Brook, N. J., assignor to New Jersey Machine Corporation, Hoboken, N. J., a corporation of New Jersey

Application November 27, 1941, Serial No. 420,609

8 Claims. (Cl. 216—55)

The invention relates to labeling machines and has for its object to provide a machine of the indicated type which is simple in construction and of maximum efficiency in operation.

The invention contemplates further the provision of a novel transporting means whereby the labels are carried or transported into applying relation to the articles to be labeled, and which co-operates in a novel manner with a novel adhesive applying means to effect the application of adhesive in a predetermined manner to the labels carried by said transporting means.

In addition the invention has for its object to provide a labeling machine in which the transporting means co-operates with a pressure or clamping means to effect the application of the labels to the articles in recurrent accurate relation thereto.

Other objects will appear from the description hereinafter and the features of novelty will be pointed out in the claims.

In the accompanying drawings, which illustrate an example of the invention without defining its limits,

Fig. 1 is a fragmentary side elevation, partly in section, of a labeling machine in which the novel features are embodied;

Fig. 2 is a sectional elevation on the line 2—2 of Fig. 1;

Fig. 3 is a diagrammatic front view illustrating the novel suction head of the transporting means and the suction control means therefor;

Fig. 4 is a fragmentary plan view partly in section, and

Fig. 5 is a rear face view of a label or other element with the adhesive applied thereto.

The machine selected for the purpose of illustrating the novel features includes a suitable frame 10 on which a container or hopper 11 of any conventional type is supported in any convenient manner for the purpose of containing a supply of labels or other elements 12 preferably in the form of an upright supply stack. Generally speaking the bottom of the container 11 is vertically adjustable by means of suitable elevating mechanism automatically controlled in a manner to periodically restore the upper end of the stack of labels or other elements 12 to a predetermined level. For this purpose the machine may include a feeler 13 vertically slidable in an upright guide 14 and connected by means of a link 15 with a bell-crank lever 16 pivoted at 17 upon the frame 10. The lever 16 carries a roller 18 adapted to be acted on by a cam 19

5 to vertically actuate the feeler 13 in operative synchronism with the means whereby the labels or other elements 12 are successively removed from the stack in the container 11; the cam 19 is carried by a shaft 20 suitably journaled in the machine.

10 The transporting means whereby individual labels or other elements 12 are successively removed from the upper end of the supply stack and transferred therefrom for adhesive application to the articles for which the labels or other elements are designed consists of a carriage 21 slidably mounted upon a fixed guide rail 22 conveniently supported on the frame 10 as shown in Fig. 1. Suitable means of conventional type is provided for slidably reciprocating the carriage 21 on the rail 22 and, as shown, comprises an arm 23 fixed on the shaft 20 and having its free end pivotally connected with a coupling rod 24 which in turn is yieldingly and pivotally connected at 25 with the carriage 21. It will be understood that the shaft 20 is rocked on its axis in properly timed relation with the other elements of the machine in any convenient and well-known manner for instance as shown in my Patent No. 2,227,816 of January 7, 1941.

15 In addition to the parts so far described the transporting means includes means on the carriage 21 and operated at the opposite ends of the reciprocatory movements thereof to respectively pick up successive labels or other elements 12 from the supply stack and to transport said labels or other elements 12 into applying relation to the 20 articles for which the labels or other elements 12 are designed. As shown in the drawings, the aforesaid means consists of a carrier or member 26 suitably mounted on the carriage 21 for vertical reciprocation thereon and provided at its lower end with a suction head 27. The latter is of novel construction and includes two members 28 located in spaced parallel relation to each other and provided with perforations in their lower surfaces. The suction head 27 including the 25 members 28 thereof is hollow and is connected with a suitable source of suction, for instance, in the following manner. For the purpose of controlling the suction in the suction head 27—28 in the predetermined manner a flexible tube 29 or its equivalent is connected with one side of a valve casing 30 supported upon the frame 10 in any convenient manner; a second flexible tube 31 or its equivalent leads from the other side of the valve 30 to a source of suction such as a 30 pump or the like. The valve casing 30 includes

an opening which is controlled by a valve 33 carried by one arm of a bell-crank lever 34 pivoted at 35 upon a bracket 36 fixed upon the frame 10, as shown diagrammatically in Fig. 3; a suitably mounted spring 37 is provided for shifting the valve 33 to its open position at the proper time in the operation of the mechanism. The other arm of the bell-crank lever 34 extends between two adjustable projections shown in the form of screws 38 carried by lugs 39 forming part of or secured to a tripping member 40 the lower forked end 41 of which straddles a shaft 42 of the machine. The member 40 carries a roller 43 in operative engagement with a cam 44 fixed upon the shaft 42, a suitable spring 45 being provided for maintaining the roller 43 in engagement with the cam 44. The cam 44 is of suitable contour to raise and lower the tripping member 40 in a manner to operate the valve 33 in accordance with the predetermined results desired and said tripping member 40 is guided in its vertical movements in any suitable manner.

For the purpose of maintaining the carrier 26 against downward movement on the carriage 21 throughout predetermined portions of its reciprocated movements, the carrier 26 is provided at its upper end with rollers 46 and 47 located upon opposite sides of a lug 48 projecting upwardly from the carrier 26. The arrangement is such that the roller 46 travels in rolling engagement with the upper or traction surface of a stationary supporting rail 49 suitably supported in the machine, while at the same time the roller 47 travels in rolling engagement with the upper or traction surface of a movable supporting rail 50. The rail 49 is formed in its upper edge with recesses 51 and 52 located in predetermined relation respectively to the stack of labels or other elements 12 and to the applying station at which the labels or other elements 12 are applied to articles A. The latter are supported in label receiving position on a suitable support 53 located in a conventional manner at the applying station of the machine. The movable rail 50 is of sufficient length to extend throughout the path of movement of the suction head 27-28 and is carried by one or more arms 54 fixed upon a shaft 55 suitably mounted in the machine and having an operating lever 56 mounted thereon. The lever 56 is operatively connected in any convenient manner with conventional mechanism operating in properly timed relation with the other elements of the machine to rock the shaft 55 and thereby raise and lower the rail 50 to correspondingly operate the carrier 26 and suction head 27-28 on the carriage 21; an example of the aforesaid arrangement is shown in my Patent No. 2,227,816 previously mentioned herein.

As the labels or other elements 12 are transported over the path to the applying station, said labels receive applications of adhesive in the form of strips a located along opposite edges or at other predetermined portions thereof, for instance, as shown in Fig. 5. The machine accordingly includes adhesive applying means consisting of adhesive applying rolls 57 located in spaced relation to each other and fixed upon a shaft 58 suitably mounted in the machine. The applying rolls 57 are located in adhesive receiving relation to a co-operating pair of adhesive distributing rolls or to a single distributing roll 59 which dips into a supply of adhesive in any well-known way. The adhesive applying rolls 57 are located in registry with those parts of the aforesaid path traversed by the members 28 of the suction head

27 as indicated in Fig. 2. Any suitable means may be provided for operating the adhesive applying means.

For co-operation with the transporting means 5 and more specifically with the suction head 27-28 in the application of the labels to the articles A in the manner to be more fully pointed out hereinafter, the machine includes a pressure means operated in predetermined synchronism 10 with the other elements of the machine. In its illustrated form the pressure means comprises a pressure member 60 preferably provided on its active face with a pad or cushion 61 and carried by a plunger 62 slidably mounted in a guideway 63 forming part of or suitably supported on the frame 10. Suitable provision is made for slidably operating the plunger 62 and its associated elements in the guideway 63. In the illustrated example a lever 64 is loosely mounted on the shaft 20 and has its free end 65 pivotally or movably connected with the plunger 62. The mechanism whereby the lever 64 is pivotally rocked may include a member 66 adjustably connected at 67 with the lever 64 and itself controlled and operated for instance in the manner illustrated and described in my Patent No. 2,227,816 referred to hereinbefore.

In practice, assuming that in Fig. 1 the parts are shown in position at the so-called label applying station of the machine subsequent to the depositing of a label 12 upon an article A, the shaft 55 will be rocked in properly timed relation with the other elements of the machine, by the lever 56 and its operating mechanism in 30 a direction to swing the arm or arms 54 and the movable supporting rail 50 in an upward direction. A lifting action will thereby be exerted on the roller 47 to raise the carrier 26 and with it the suction head 27-28 on the carriage 21 to a 35 position above that illustrated in Fig. 1 so that the active faces of the members 28 of the suction head 27 are at a level higher than that of the adhesive applying rolls 57.

As the shaft 20 is now rocked on its axis, the lever 23 will be swung to the right in Fig. 1 and by means of the coupling rod 24 will slidably pull the carriage 21 in the same direction lengthwise of the rail 22 to a position in which the members 28 of the suction head 27 will be located above 45 and in registry with the upper end of the stack of labels 12 in the container 11. During these operative steps, the cam 19 partakes of the rocking movement of the shaft 20 and by acting on the roller 18 will swing the bell-crank lever 16 in a direction to raise the feeler 13 away from the upper end of the supply stack of labels 12 to an inoperative position in which it does not interfere with the subsequent actuation of the suction head 27 and its members 28 in the removal 50 of a terminal label 12 from said supply stack.

As the carriage 21 is thus slidably moved to the right on the guide rail 22, the roller 47 will travel lengthwise of the elevated supporting rail 50 to maintain the carrier 26 in a raised position on the carriage 21, in which raised position the active faces of the members 28 of the suction head 27 are at a common level higher than the adhesive applying rollers 57 and accordingly do not contact therewith. At the end of this 60 sliding movement toward the right the roller 46 will be above and in registry with the recess 51 of the stationary supporting rail 49 with the roller 47 still in rolling engagement with the elevated supporting rail 50. At the proper moment the shaft 55 will be rocked in a direction 65

to swing the arm or arms 54 downwardly to thereby lower the supporting rail 50 and with it the carrier 26 on the carriage 21. At this stage the roller 46 moves downwardly into the recess 51 of the rail 49 and the members 28 of the suction head 27 move into engagement with the upper end of the supply stack of labels 12 in contact with the opposite ends of the upper terminal label 12 thereof.

During these operations the shaft 42 of the machine is being rotated so that the cam 44 in co-operation with the roller 43 and spring 45 will cause the tripping member 40 to move downwardly. This will cause the upper projection or screw 38 to exert a pressure on the bell-crank lever 34 whereby the latter is pivotally swung in a direction to adjust the valve 37 to its closed position in which the suction conduit is sealed against the atmosphere. As a result of this, suction will be automatically developed in the members 28 of the suction head 27 in proper operative synchronism with the aforesaid operative steps and accordingly will cause the opposite ends of the terminal label 12 of the supply stack to adhere to the active faces of said members 28.

When this suction connection between the opposite ends of the terminal label 12 and the members 28 of the suction head 27 has been established, the shaft 55 and arm or arms 54 will be rocked in a direction to elevate the supporting rail 50 and roller 47 to thereby raise the carrier 26 and suction head 27 with the terminal label 12 adhering to and spanning the space between the members 28 of said suction head 27, and to concurrently lift the roller 46 out of the recess 51 to the level of the traction surface of the stationary supporting rail 49. At this stage, the mechanism will be operated to slidably shift the carriage 21 along the guide rail 22 toward the left in Fig. 1, the roller 46 meanwhile traversing the fixed supporting rail 49 to thereby maintain the carrier 26 and its associated parts in the aforesaid raised position as the carriage 21 travels along the guide rail 22 in the indicated manner. In the meantime the associate roller 47 may travel along the supporting rail 50 or the latter may be moved downwardly and away from said roller 47 at the beginning of the aforesaid operations.

In this position of the parts, the lowest surface of the label 12 carried by the members 28 of the suction head 27 is at the level of the adhesive applying rolls 57 and accordingly at its opposite end portions will be caused to pass over in tangential surface contact with said adhesive applying rolls 57 as the carriage 21 travels to the left. The lower surface of said label 12 will therefore receive coatings of adhesive in the forms of strips *a* along its opposite edges as illustrated in Fig. 5. The travel of the carriage 21 to the left in Fig. 1 will finally cease and said carriage will come to rest with the roller 46 located above and in registry with the recess 52 of the stationary supporting rail 49 and the suction head 27 with the label 12 carried by and extending between the members 28 thereof in label applying relation to the particular article A located on the support 53 at the time.

In proper operative synchronism the shaft 55 is rocked in a direction to swing the arm 54 and supporting rail 50 downwardly to thereby lower the carrier 26 on the carriage 21 to cause the suction head 27 or more specifically the members 28 thereof to bring the label 12 carried thereby into tangential relation and contact with

the article A as illustrated in Fig. 3. In predetermined timing the lever 64 will be operated to shift the plunger 62 downwardly in the guideways 63 and to bring the pad 61 of the pressure member 60 into contact with the label 12 to press the central portion of said label 12 which is not coated with adhesive, firmly against the article A to thereby securely fix said label 12 in position on said article A.

After the pressure member 60 with its pad 61 has thus clamped the label 12 against movement relatively to the article A, the cam 44 acting on the roller 43 will raise the tripping member 40 to cause the lower projection or screw 38 to engage the bell-crank lever and swing the latter in a direction to shift the valve 37 to its open position. As this occurs the suction will be relieved in the members 28 of the suction head 27 and the opposite ends of the previously carried label 12 will be released and the adhesive attachment of said label 12 to the article A will be completed in any conventional manner.

It is to be particularly noted that the suction is relieved to release the opposite ends of the label 12 after the central portion of said label 12 has been firmly clamped on the article by the pressure member 60 and its pad 61. Thus even though the intermediate portion of the label 12 is free from adhesive the label is accurately applied to the article A and firmly held in the predetermined position in which all subsequent labels 12 are applied to subsequent articles A with corresponding accuracy.

It will be understood that the arrangement may be such that the strips of adhesive *a* are applied to the labels 12 in spaced parallel relation otherwise than along the opposite edges thereof.

The mechanism set forth is of maximum reliability and operation and predetermines an accurate and uniform application of the labels 12 to the articles A for which they are designed.

Although the present invention has been described in conjunction with a preferred embodiment, it is to be understood that modifications and variations may be resorted to without departing from the spirit and scope of the invention, as those skilled in the art will readily understand. Such variations and modifications are considered to be within the purview and scope of the claims.

I claim:

1. In a labeling machine, the combination of a holder for a supply of labels, a support for articles to be labeled, transporting means for removing labels from said supply and depositing said labels upon and in contact with said articles, means for clamping said deposited labels on said articles, and means independent of said clamping means for effecting the release of said labels from said transporting means subsequent to the clamping of said deposited labels on said articles to permit the application of said labels to said articles to be completed.

2. In a labeling machine, the combination of a holder for a supply of labels, a support for articles to be labeled, transporting means including a suction head for removing labels from said supply and depositing said labels on said articles, pressure means for clamping said deposited labels on said articles, and means for relieving the suction in said suction head subsequent to the clamping of said deposited labels on said articles whereby said labels are released from said suction head.

3. In a labeling machine, the combination of a holder for a supply of labels, a support for articles to be labeled, adhesive applying means, transporting means for transferring labels from said supply into adhesive receiving relation to said adhesive applying means and for subsequently depositing said labels on said articles, means for clamping said deposited labels on said articles, and means for effecting the release of said labels from said transporting means subsequent to the clamping of said deposited labels on said articles.

4. In a labeling machine, the combination of a holder for a supply of labels, a support for articles to be labeled, spaced adhesive applying rolls, transporting means including a suction head having spaced members for engaging terminal labels of said supply at spaced points and transferring said labels into adhesive receiving relation to said adhesive applying rolls to receive spaced strips of adhesive as coatings therefrom and for subsequently depositing intermediate uncoated portions of said labels on said articles, a pressure member for clamping said uncoated portions of said labels on said articles, and means for relieving the suction in said suction head subsequent to the clamping of said deposited labels on said articles whereby said labels are released from the members of said suction head.

5. In a labeling machine, a suction head comprising two spaced members of corresponding elongated form having perforated active faces for developing coincidental suction grips in linear contact with spaced portions of a surface of a label, and a member connecting said spaced mem-

bers and supporting the latter in fixed relation to each other.

6. In a labeling machine, a suction head comprising a carrying member and spaced members of corresponding elongated form projecting transversely from opposite ends of said carrying member in fixed transverse relation thereto and in fixed relation to each other, said spaced members having perforated active faces for developing coincidental suction grips in linear contact with spaced portions of a surface of a label.

7. In a labeling machine, a suction head comprising a carrying member and spaced members projecting from opposite ends of said carrying member in spaced parallel relation for engaging and holding labels at spaced points, and adhesive applying rolls for applying strips of adhesive to said labels in registry with the members of said suction head.

8. In a labeling machine, a suction head comprising a carrying member and spaced members projecting from opposite ends of said carrying member in spaced parallel relation for engaging and holding labels at spaced points, adhesive applying rolls for applying strips of adhesive to said labels in registry with the members of said suction head, a pressure member operative between the spaced members of said suction head for clamping adhesive free portions of said labels on articles, and means for relieving the suction in said suction head subsequent to the clamping of said adhesive free portions of said labels on said articles whereby said labels are released from the spaced members of said suction head.

GEORGE W. von HOFE.
